Inventor

UNITED STATES PATENT OFFICE.

HERBERT E. LYNCH, OF BROOKLYN, NEW YORK.

TELEPHONE INSTRUMENT.

1,196,562.

Specification of Letters Patent. Patented Aug. 29, 1916.

Application filed April 9, 1915. Serial No. 20,305.

To all whom it may concern:

Be it known that I, HERBERT E. LYNCH, a citizen of the United States of America, residing at Brooklyn, in the county of Kings and State of New York, have invented new and useful Improvements in Telephone Instruments, of which the following is a specification.

This invention relates to improvements in telephone instruments and has particular application to a combined transmitter and receiver.

In carrying out the present invention, it is my purpose to provide a combined transmitter and receiver wherein the receiver and transmitter will be carried in a single casting so that a conversation may be carried on without necessitating the holding of the receiver to the ear of the user of the instrument, thereby enabling the person using the instrument to use the hands for writing or other purposes while carrying on a conversation.

It is also my purpose to provide a telephone instrument of the class described, which will embrace the desired features of simplicity, efficiency and durability, which will operate efficiently and effectively to transmit and reproduce sound waves and which may be manufactured at small cost.

With the above and other objects in view, the invention consists in the construction, combination and arrangement of parts hereinafter set forth in and falling within the scope of the claim.

In the accompanying drawing; Figure 1 is a view in side elevation of a combined telephone transmitter and receiver constructed in accordance with the present invention. Fig. 2 is a view in front elevation thereof. Fig. 3 is a fragmentary sectional view through the instrument.

Referring now to the drawing in detail, 1 designates a base constructed of any suitable or preferred material, while 2 indicates a standard uprising from the base. Fastened to the upper end of the standard 2 in some suitable manner and having the longitudinal axis thereof disposed at right angles to the standard 2 is an amplifying horn 3 having the small end thereof secured to the standard and the relatively large end projecting outwardly from the standard. Disposed within the relatively small end of the ampli-

fying horn 3 and suitably fastened therein is 55 a telephone receiver comprising a sound reproducing diaphragm 4 and electromagnets 5 adapted to vibrate the sound diaphragm in accordance with the magnetic flux set up by the undulatory current traversing the 60 coils of the magnets. Disposed within the relatively large end of the sound amplifying horn 3 is a transmitter 6 of any usual or preferred construction. In the present instance, this transmitter is disposed approximately centrally of the relatively large end 65 of the horn and is secured in position by means of supporting rods 7 radiating from the transmitter and having the outer ends thereof fastened to the outer edge of the 70 horn, the rods being spaced apart equal distances so that the transmitter will be supported with uniformity. If desired, a hand operated switch may be employed to make and break the talking circuit and this switch 75 is preferably carried by the standard 2 adjacent to the upper end thereof within convenient reach of the user of the telephone instrument.

In practice, the sound waves reproduced 80 by the diaphragm 4 under the action of the magnets 5 are amplified by the horn 3 and emerge from the relatively large end of the horn while the sound waves sent into the transmitter 6 by the user of the instrument 85 are reproduced at the other end of the line in a like manner. It will be seen that I have provided a telephone instrument whereby the user can both hear the reproduced sound waves and transmitted sound waves 90 without the necessity of holding the receiver to the ear as is now usual.

While I have herein shown and described the preferred form of my invention by way of illustration, I wish it to be understood 95 that I do not limit or confine myself to the precise details of construction herein described and delineated, as modification and variation may be made within the scope of the claim without departing from the spirit 100 of the invention.

I claim:

In a combined telephone transmitter and receiver, a base, a hollow standard uprising from said base, an amplifying horn on the 105 upper end of said standard at right angles thereto, a transmitter arranged in the large end of said horn centrally thereof, support-

ing rods secured to said transmitter and radiating therefrom and having the outer ends thereof secured to the adjacent edge of said horn, a receiving magnet arranged in said standard, a casing secured to the core of said magnet and a diaphragm supported by said casing at the small end of said horn.

In testimony whereof I affix my signature in presence of two witnesses.

HERBERT E. LYNCH.
